UNITED STATES PATENT OFFICE.

THEODOR KNOBLICH, OF HAMBURG, GERMANY.

MOVABLE LETTERS FOR ADVERTISING-BOARDS.

SPECIFICATION forming part of Letters Patent No. 726,702, dated April 28, 1903.

Application filed January 13, 1902. Serial No. 89,615. (No model.)

To all whom it may concern:

Be it known that I, THEODOR KNOBLICH, mechanician, a subject of the German Emperor, residing at 43 Pferdemarkt, Hamburg, 5 in the German Empire, have invented new and useful Improvements in Movable Letters for Advertising-Boards, of which the following is a specification.

My invention relates to movable letters for advertising purpose, which either singly or connected together so as to form words and either in or not in connection with other immovable letters shall be used for advertising words, for the purpose to draw the attention 15 of the public through either movement to such advertisements with which they are connected.

The accompanying drawings illustrate the object of this invention in different modes of 20 construction.

Figure 1 shows an elevation of the intended advertisements. Fig. 2 shows the arrangement for moving the single letters so as to swing horizontally. Fig. 3 shows the moving 25 arrangement in section. Fig. 4 shows the moving of the horizontal letter - bearer by means of a tooth-wheel and ratchet-levers. Fig. 5 illustrates the vertical moving of the letters by means of a horizontal curve-wheel, 30 and Fig. 6 the horizontally-swinging movement by means of a cam.

The arrangements shown in Figs. 1 to 4 and in Fig. 6 are for the purpose to give to every 35 single letter a horizontally-swinging motion on its center point or fulcrum, respectively. The driving power as shown in the drawings is a clockwork, but can, and especially in large plants, be formed by a motor of any description or by a line of shafting and from 40 any source of power.

The letters "a" are fastened in their center to a pin *b*, which pivots in the plate *p*. To each pin is fixed a crank *c* with a pin *d*, which latter pass through holes or slots of a rod or 45 rail *s*. The rod *s* has a pin *i* passing through the slot *g* of the lever *h*. This lever *h* is part of the pawl-and-ratchet arrangement *f*. This arrangement *f* by means of its arms *k* is alternately in contact with the teeth of the tooth- 50 wheel *m*, which latter one is driven so as to turn around by any kind of spring-power *l*, so that by the turning of wheel *m* the lever

h gets a swinging motion. In Fig. 6 this swinging movement of the lever is arrived at by prolonging the lever *h* over its fulcrum *n* 55 and by providing the prolongation *q* with a pin *o*, which by means of a curved slot *r* in the disk *t* is guided for the required movement. The prolongation *q* of the lever *h* has a balance-weight *u*, so as to make the pen- 60 dulum-like movement stronger and more energetic.

The above-described arrangement works as follows: The pendulum-like movement of the lever *h*, accomplished by the tooth-wheel *m* 65 or the cam-disk *t*, is transmitted to the rod *s* by the pin *i*, sliding in the slot *g* of the lever *h*. The rod *s* therefore gets a forward-and-backward motion horizontally, which motion is transmitted to the letters "a," which are 70 pivoted in the plate *p*, by means of the crank-pins *d*, passing through the holes *c*. For this reason every letter swings to and fro on its pivot *b*.

In the arrangement shown in Fig. 5 the 75 pins of the letters "a" are not pivoted in the plate *p*, but are connected directly and rigidly to the rail *s*. This rail *s* is fixed to a rod *v*, guided in the guides *w*, and the bottom end of which has a pin *x*, which is guided for the 80 required movement in the curve-slot *r* of the horizontally-turning curve-disk *t* in such a manner that the rod *v*, and in connection with this the rail *s*, with the letters "a," receives a continuously up-and-down movement 85 corresponding with the pitch of the curve-slot *r*. In this construction the plate *p* must be provided with a vertical slot for each letter.

The plate *p* can be made of transparent material and illuminated from the back at 90 will, and the single letters can consist of or be supplied with electrical incandescent lamps. The single letters can be arranged so as to be removable, so that they can be put on or off, as desired, which facilitates the 95 forming of different words for the advertisements. This movable advertising arrangement can be made so as to have only one, or it may have more, faces, and in the latter case the letters of all sides can be moved 100 from one driving arrangement.

Having now particularly described this invention and in what manner the same is to be performed, what I claim, and desire to se-

cure by Letters Patent of the United States, is—

5 An advertising device comprising a board, cranks having bearings in the board, letters on the cranks, a rail connecting the cranks, a pin extending from the rail, a lever having a slot to receive said pin, and means for imparting swinging motion to the lever.

In testimony that I claim the foregoing as my invention I have signed my name in presence of two subscribing witnesses.

THEODOR KNOBLICH.
